PORTABLE BREAKER UNIT WITH BAR-SCREEN SEPARATOR IN THE MATERIAL FEED STRUCTURE

Raymore D. MacDonald, La Grange, Ill., assignor to Athey Products Corporation, Chicago, Ill., a corporation of Illinois

Application January 6, 1949, Serial No. 69,492

8 Claims. (Cl. 241—81)

1

This invention relates to portable breaker units, and more particularly to such units adapted to use as a towed trailer and in conjunction with a loader or the like for feeding material thereto during movement.

One of the objects of my invention is to provide a portable breaker unit of the type referred to and which is constructed and arranged to utilize the inertia of the material delivered thereto for effecting reductions of the size and amounts of material delivered to the crusher.

Considered in more detail, my invention has within its purview the provision of impact elements and a grate in the path of movement of material to the crusher for effecting primary separation of fine material from larger pieces and the by-passing of such fine material relative to the crusher.

As another object, this invention comprehends the provision of spring loaded trap elements past which material is fed into a crusher, and which elements prevent such material or particles thereof from being thrown out of the crusher as a result of impact.

My invention further comprehends the provision of a portable breaker embodying one or more of the foregoing characteristics and wherein the construction and arrangement is such that the main support is provided by two wheels and a prime-mover is included thereon for driving the crusher.

It is another object of the invention to provide a portable breaker wherein material is fed to a hopper at the top in which fine material is separated from that to be crushed and from which the fine material passes directly to an outlet chute, while the coarser parts go through a crusher and thence to an outlet positioned so that all of the material together forms a windrow.

Other objects and advantages of the invention will be apparent from the following description and the accompanying drawings in which similar characters of reference indicate similar parts throughout the several views.

In the three sheets of drawings,

Fig. 1 is a top plan view of a portable breaker unit embodying a preferred form of my invention;

Fig. 2 is a side elevational view of the breaker unit shown in Fig. 1, wherein an associated loader is fragmentarily shown in dot and dash lines;

Fig. 3 is a rear sectional view of the loader unit, wherein the section is taken substantially on a line 3—3 of Fig. 2 and in the direction indicated by arrows;

Fig. 4 is a fragmentary top sectional view wherein the section is taken substantially on a line 4—4 of Fig. 2 and in the direction indicated by accompanying arrows; and

2

Fig. 5 is a fragmentary sectional view of a part of the structure which is shown in Fig. 2.

Considering the general structure and arrangement of the preferred and exemplary embodiment of my invention, which is disclosed in the accompanying drawings for illustrative purposes, my preferred breaker unit embodies an underframe 10 supported by coaxially disposed wheels 12 and 13 which are mounted at the sides of the unit on an axle 14 extending through the underframe. On the top of the underframe and at the rear of the unit, a crusher 15 of one of the generally known types is mounted. For the purpose to which this unit is adapted, it is my preference to utilize a power driven rotary impact crusher. Also, on the top of the underframe 10 and spaced forwardly of the crusher, a prime-mover 16 is mounted for limited movement longitudinally of the underframe. The prime-mover, in this instance, comprises a diesel type internal combustion engine drivingly connected to the crusher through a plurality of flexible driving elements 17 such as a series of V-belts in parallel relationship. A hopper 18 is mounted above the crusher and is supported partially by the crusher and partially by upright frame members 19 secured to the underframe between the crusher and the prime-mover. As depicted in Figs. 1 and 2, the hopper has a material receiving opening 20 facing forwardly of the unit and through which an aggregate of coarse and fine material is adapted to be fed by a loader including a conveyor 22, as indicated in Fig. 2.

Considered in greater detail, the underframe 10 of my preferred structure includes longitudinally extending side channels 23 and 24 secured at separated positions to cross-beams 25, 26, 27 and 28. At the front of the unit, a towing yoke is provided by front channels 29 and 30 secured to the forward ends of the side channels 23 and 24 and secured together at their forward ends to form a V mid-way between the side channels. Bracing for the yoke is provided by formed top plate 32 and longitudinally extending braces 33 and 34 secured to the front channels 29 and 30.

The disclosed portable breaker unit being adapted to operation while being towed at the rear of a loader, the breaker unit has a coupling unit 35 secured to the mid-portion of the lower side of the front yoke. This coupling unit, in the present instance, includes telescoped cylinders 36 and 37 which enclose and are biased longitudinally relative to one another by a compression spring 41 (Fig. 5) which absorbs shock during the towing operation. As depicted, a link 38 at the front of the cylinder 37 connects flexibly to a fixture 39 secured to the rear of the loader.

In the preferred arrangement of my breaker unit, the placement of the parts, including the crusher 15, prime-mover 16 and hopper 18, on

the underframe 10 is such that the weight of the unit is quite closely balanced forwardly and rearwardly of the axis of the wheels 12 and 13. Thus, the wheels, through the axle 14, carry a very high percentage of the entire weight of the unit, and only relatively small vertical forces are normally transmitted through the coupling 35. For static stability, as well as for satisfactory operation, without placing an undue burden upon the towing machine, the normal balance of the weight relative to the axis of the wheels is such that there is a nominal force downwardly at the forward end of the unit. Such force may be, for example, a few hundred pounds.

Thus, to provide support for the forward end of the unit when it is detached from a towing unit or not in use, a leg 40 is mounted for vertical swinging movement relative to a shaft 42 at the forward end of the coupling unit 35. This leg has at its free end a supporting foot 43 and is braced in a load supporting position, as depicted in Fig. 2, by a suitable collapsible or hydraulically operated jack 44, one end of which is secured to the mid-portion of the leg 40 and the other end of which is secured to a bracket 45 at the rear of the coupling unit 35.

While different known types of crushers are well suited to the crushing of different kinds of materials, and may be substituted in the disclosed unit, it is my preference for general use including road work to utilize a rotary impact mill. This crusher 15 in the form disclosed, has a housing 46 with a flanged material feeding opening 47 at the top. A shaft 48 is journaled in the housing 46 and carries impact hammers 49 of the usual type internally of the unit. Externally of the crusher and at one end of the shaft 48, a flywheel 50 is secured to the shaft; while at the other end of that shaft a multiple groove pulley unit 52 is secured thereto. In the ensemble, the crusher 15 is secured to and carried by the cross-beams 25 and 26.

As has been previously mentioned, the disclosed prime-mover 16 for the crusher is a diesel type internal combustion engine. At one end, the drive shaft of this engine carries a multiple groove pulley unit 53 in alignment with the pulley unit 52 on the crusher. The belts 17 provide a driving connection between the pulley units. For the purpose of effecting limited movement of the prime-mover longitudinally of the underframe to adjust the belt tension, I have provided an adjusting screw 54 carried by a bracket 55 on the cross beam 27 which serves as an aid in positioning the prime-mover when the hold-down bolts have been loosened.

The hopper 18, in the disclosed unit, has opposed side plates 56 and 57 which, by preference, define opposite sides of the relatively wide feeding opening 20 and converge rearwardly and downwardly to the opening 47 in the top of the crusher housing. Substantially triangular lower portions 58 and 59 of the side plates 56 and 57 are formed inwardly, so that the opposite sides of the hopper converge downwardly adjacent the feeding opening. Intermediate the lower ends of those downwardly converging lower portions 58 and 59 of the side walls, a grate 60 is formed by a multiplicity of spaced and longitudinally extending slats 62; the forward ends of the slats being secured to a cross member 63 carried by the upright frame members 19, and the rear ends of those slats being secured to a cross angle member 64 in the hopper structure. The grate 60, thus formed, slopes downwardly from the hopper feeding

opening 20 to a formed apron 65 adjacent the forward edge of the crusher feeding opening 47. At the rear and top, the hopper is closed, respectively, by a substantially vertical rear plate 66 and a top plate 67. Preferably, flanges 68 are provided adjacent the hopper feeding opening 20 to reinforce the hopper structure adjacent that opening.

Below the hopper 18, extending downwardly beneath the grate 60, an outlet chute 69 is provided for the flow of fine material which passes through the grate 60. This outlet chute is defined along its front surface by a front plate 70 secured to the upright frame members 19 and extending downwardly from the cross member 63 to a cross member 72. On opposite sides, as depicted in Fig. 3, the outlet chute 69 is defined by side plates 73 and 74 which adjoin the lower edges of the triangular lower portions 58 and 59 of the side plates 56 and 57 and extend downwardly, with their lower ends secured to the inner surfaces of longitudinal channels 75 and 76. A rear plate 77 adjoins the front edge of the apron 65 at the top and extends downwardly ahead of the axle 14 to the cross-beam 26, and is secured thereto. Thus, material which is sufficiently fine to pass through the grate 60 flows downwardly through the outlet chute 69 and is discharged in front of the axle 14 to form a windrow below the mid-portion of the crusher unit as it moves along during operation. Such fine material thus by-passes the crusher.

In addition to the grate 60 which effects separation between fine material for passage from the hopper through the outlet chute 69, so as to limit the amount of material which passes through the crusher, I have provided additional means for effecting the primary separation of fine material from coarser material to which it has adhered, as well as for effecting some possible preliminary breakage of larger lumps or pieces in the aggregate material. Preferably, the loader with which this crusher unit is utilized operates so as to throw the material from the upper end of the conveyor 22 at a relatively high velocity; such velocity being sufficient that the material is thrown into the hopper opening 20, rather than merely falling off the upper end of the conveyor 22 so as to slide into the hopper. Then, in order advantageously to utilize the relatively high velocity of the material as it enters the hopper opening 20, a series of striker bars 78 is provided, which striker bars are hung for individual swinging movement from a cross shaft 79 carried by brackets 80 internally of the top of the hopper 18 and inwardly of the face of the hopper opening 20. A channel 82, by preference, extends across the exterior of the hopper in parallel relationship to the cross shaft 79 and has the brackets 80 secured thereto for effecting reinforcement of the hopper and support for the striker bar assembly.

The striker bars 78 are relatively heavy and preferably extend downwardly from the cross shaft 79 to a level near the lower edge of the hopper opening 20, so as to intercept material thrown into the hopper from the end of the conveyor, thereby to provide an impact with that moving material which is sufficient to jar the fine material from the coarser pieces and effect some breakage of weak coarser pieces. It has also been found more effective in operation to utilize striker bars of a sectional shape such that the material strikes relatively narrow forward edges of the bars, although those bars have a depth

sufficient to provide the desired mass and rigidity. Furthermore, the bars of the series are hung in spaced relationship laterally of the hopper opening, with the bars of the series spread across substantially the entire width of the hopper opening. As another consideration, the mass of the striker bars is such that in addition to providing an impact with the pieces of material, they are moved rearwardly within the hopper to permit the passage of larger pieces, rocks and the like to the opening 41 at the top of the crusher. Being hung over the mid-portion of the grate, the smaller pieces of material are directed downwardly by the striker bars to the grate for grading, whereupon the larger pieces, thus deflected, slide down the sloping grate surface to the crusher opening.

Provision is made by a trap 83 for the prevention of material from being thrown, by impact within the crusher, back through the crusher opening 41 into the hopper and even from the hopper opening. Such provision is of particular importance when, as in the present instance, a rotary impact mill is used which has impact hammers 49 operating at relatively high speed to effect the crushing of the material. In my preferred structure, and as depicted in Figs. 2 and 4, the trap 83 includes a plurality of slats 84 which, in the present instance, are of channel section mounted in adjacent, side-by-side relationship above the opening 41. As depicted in Fig. 2, the slats 84 are supported at one end by a cross shaft 85 supported internally of and adjacent the rear plate 66 of the hopper by brackets 86 secured to the hopper side wall 56 and 57. The shaft 85 provides an upper support upon which the slats 84 are mounted for individual swinging movement, and from which upper support the slats extend downwardly and forwardly to a position underlying the edge of the apron 65 at the forward edge of the opening 41. Thus, upward or counterclockwise swinging movement of the slats, as viewed in Fig. 2, is limited by their engagement with the edge of the apron 65, in which position they provide an effective closure wall between the interior of the crusher and the interior of the hopper. The slats are movable, however, in a clockwise direction, as viewed in Fig. 2, to a position in which they lie along the inner surface of the rear plate 66, if necessary, for permitting the flow of material from the hopper into the crusher.

Projecting arms 86 secured to each of the slats 84 at the shaft supported ends thereof, project outwardly of the hopper through suitable slots in the rear plate 66 thereof. These arms 86 serve as levers, to each of which is connected one end of a tension spring 87, the other end of such spring, in each instance, being adjustably anchored through an eye-bolt 88 to a bracket 89 projecting from the lower end of the rear plate 66 near the crusher opening 41. The tension springs 87 thus individually bias the slats 84 to positions, as indicated in Fig. 2, in which the lower ends of those slats engage the edge of the apron 65. In this manner, the slats 84 are normally biased to a position in which they effectively close the crusher opening 41, although the biasing force is so adjusted that the weight of material against the surfaces of the slats which are exposed within the hopper moves those slats out of the way to an extent that the material can pass into the crusher. Provision for adjustment of the biasing force exerted upon the slats is made by the inclusion of spaced apertures 90, 92 and 93 in arms

86 for varying the effective lever length through which the force of the springs 87 operate.

The discharge opening for the crusher, although not shown, is, by preference, located in the lateral mid-portion of the crusher and behind the lower end of the discharge chute 69, so that the combined discharge of fine and crushed material forms a single windrow as the crusher unit moves forwardly during operation. As a further preference, I have provided an apron 94 which is secured to the front of the hopper 18 immediately below the opening 20, which apron projects forwardly to a position such that it normally underlies the end of a feeder conveyor during the operation of the crusher unit to catch any material which falls from the end of the conveyor, particularly when the operation is slow during the starting or stopping.

From the foregoing description and reference to the accompanying drawings, it may be readily appreciated that I have provided a rugged portable crusher unit which is adapted to use while being towed at the rear of a high speed loader and which by virtue of its construction and arrangement, is capable of effectively handling large quantities of aggregate material. The effectiveness and capacity of the unit are enhanced by utilizing the individually movable striker bars for producing an impact with the material entering the hopper and at a position such that the force of the impact not only reduces the size of pieces, but also aids in the separation of fine and coarser material before such material enters the crusher. As a safety factor, I have provided the trap parts separately movable to permit the flow of material into the crusher while preventing impact within the crusher from throwing any sizable pieces of material therefrom.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States is:

1. A portable crusher unit adapted to receive an aggregate of coarse and fine material fed thereto at relatively high velocity and comprising, in combination, a hopper having an opening at the top of the front thereof through which the aggregate is fed thereto, a plurality of striker bars aligned laterally of the opening and each hung for swinging movement interiorly of the opening, said striker bars normally extending to positions in the hopper for impact with the material entering the opening, an impact crusher below the hopper and having communication with the hopper through a passage at the rear of the bottom portion of the hopper, a grate in the hopper sloping downwardly from a position below said opening to the front of said passage, means providing an outlet passage for fine material below the grate and in front of the crusher, said crusher having an outlet opening behind said outlet passage, a prime-mover for driving the crusher, and an underframe supported by two coaxial wheels, said crusher, hopper and prime-mover being mounted on the underframe so that a high percentage of the weight thereof is balanced on opposite sides of the wheel axis.

2. A portable crusher unit as defined in claim 1,

and wherein said passage between the hopper and crusher is normally closed by a plurality of adjacent slat members supported for swinging movement relative to a common axis and individually biased to closed positions, said slat members each being swingable against the biasing force by the weight of material fed thereagainst in the hopper to permit flow of the material into the crusher.

3. A portable crusher unit adapted to receive an aggregate of coarse and fine material fed thereto at relatively high velocity and comprising, in combination, a hopper having an opening at the top of the front thereof through which the aggregate is fed thereto, a plurality of striker bars aligned laterally of the opening and each hung for swinging movement interiorly of the opening, said striker bars normally extending to positions in the hopper for impact with the material entering the opening, an impact crusher below the hopper and having communication with the hopper through a passage at the rear of the bottom portion of the hopper, a plurality of slat members hingedly supported in adjacent side-by-side relationship for separate swinging movements to and from positions for effecting closure of said passage, said slat members being individually biased to said positions for effecting closure of the passage and movable against the biasing force by the weight of material thereagainst for permitting flow of material into the crusher, said crusher having an outlet opening therein through which crushed material is discharged therefrom, a prime-mover for driving the crusher, and an underframe supported by two coaxial wheels, said crusher, hopper and prime-mover being mounted on the underframe.

4. A portable crusher unit as defined in claim 3, and further characterized by a towing coupling at the front end of the underframe and including resilient means for absorbing end thrusts, and a foot hingedly secured to the front end of the underframe for supporting that end of the unit when such unit is stationary.

5. A portable crusher unit adapted to receive an aggregate of coarse and fine material fed thereto and comprising, in combination, a hopper having a generally upright opening through which the aggregate is fed thereto, a crusher below the hopper and having communication with the hopper through a passage at the bottom portion of the hopper, a grate in the lower portion of the hopper below said opening and adjacent said passage and sloping downwardly toward the passage, means hung for swinging movement interiorly of said hopper opening and aligned with the opening for deflecting material from the opening to said grate, an extension on the hopper below the grate and providing an outlet passage for fine material, said crusher having an outlet for the discharge of crushed material, a prime-mover for driving the crusher, an underframe upon which the crusher, hopper and prime-mover are mounted, and means including a pair of aligned wheels having an axis located near a position of weight balance longitudinally of the underframe for supporting the underframe.

6. A portable crusher unit as defined in claim 5, and further characterized by a plurality of slat members hingedly supported in side-by-side relationship for separate swinging movements to and

from positions for effecting closure of said passage between the hopper and crusher, and springs separately biasing said slat members to said positions for effecting closure of the passage, whereby the slat members are movable against the biasing force of the springs for the flow of material from the hopper to the crusher.

7. A portable crusher unit as defined in claim 5, and wherein said means hung for swinging movement interiorly of the hopper opening is characterized by a plurality of relatively heavy striker bars each hung for swinging movement in the path of material entering the hopper through said opening, said bars normally being lateral to direction of flow of material into the hopper and disposed at positions above said grates.

8. A portable crusher unit adapted to receive an aggregate of coarse and fine material fed thereto at relatively high velocity and comprising, in combination, a hopper having an opening at the top of the front thereof through which the aggregate is fed thereto, means suspended for swinging movement interiorly of the opening and laterally aligned with the opening, said means normally extending to a position in the hopper for impact with the material entering the opening, an impact crusher below the hopper and having communication with the hopper through a passage at the rear of the bottom portion of the hopper, a plurality of slat members hingedly supported in side-by-side relationship for swinging movements to and from a position for effecting closure of the passage, said slat members being biased to said position for effecting closure of the passage and movable against the biasing force by the weight of material thereagainst for permitting flow of material into the crusher, said crusher having an outlet opening therein through which crushed material is discharged therefrom, a prime-mover for driving the crusher, and an underframe supported by means including wheels, said crusher, hopper and prime-mover being mounted on the underframe.
